UNITED STATES PATENT OFFICE.

SAMUEL G. CABELL, OF WASHINGTON, DISTRICT OF COLUMBIA, ASSIGNOR
TO FLORA B. CABELL, OF SAME PLACE.

OIL-CUP.

SPECIFICATION forming part of Letters Patent No. 237,660, dated February 8, 1881.

Application filed January 12, 1881. (No model.)

To all whom it may concern:

Be it known that I, SAMUEL G. CABELL, of Washington, in the county of Washington and District of Columbia, have invented a certain new and useful Improvement in Oil-Cups; and I do hereby declare the following to be a full, clear, and exact description of the same, reference being had to the accompanying drawings, forming part of this specification, in which—

Figure 1 represents a longitudinal vertical section of the invention; Fig. 2, a detail view, showing the application of a supplementary oil-reservoir; Fig. 3, a top view of the yoke. Fig. 4 is a view showing the application of the invention to the steam-chest of a locomotive. Fig. 5 is a view of a modified arrangement for feeding the oil in under the piston.

Similar letters of reference in the several figures denote the same parts.

My invention has for its object to provide an improved oil-cup for introducing oil into the steam chests and cylinders of steam-engines, particularly locomotive-engines, for the purpose of properly lubricating the valves, pistons, &c., in such parts, and which shall be adapted to feed automatically a constant and uniform supply of oil, and also to be so adjusted as to regulate accurately the quantity of oil thus fed.

To this end my invention consists, broadly, in an oil-chamber jacketed and heated by steam to prevent condensation, having a piston operated by gravity or other equivalent force to insure the feeding of the oil, with oil supply and discharge openings or passages, and with suitable provision for substantially balancing the steam-pressure on each side of the piston.

It further consists in an oil-chamber jacketed and heated by steam, a piston arranged in said chamber, a passage or passages leading from below the piston to the steam-chest, and a passage or passages for admitting steam above the piston.

It further consists of an oil cup or chamber arranged within an outer casing or shell, so as to leave a steam-space between the two communicating with the steam-chest or part to be lubricated, a piston adapted to fit within said

oil-chamber, and passages leading from the steam-space to the oil-chamber above and below said piston.

It further consists in the provision of means for regulating the steam-pressure on the piston.

It further consists in a novel arrangement for supplying oil to the oil-chamber.

It further consists of certain other novel details of construction; and it consists, lastly, in an improvement in the art of lubricating, all which will be hereinafter fully set forth.

In the accompanying drawings, A represents an oil-chamber; B, an outer case or shell surrounding the same, with a steam-space, C, between the two, as shown. The case or shell B is provided with a tubular stem, b, which is preferably screw-threaded externally to adapt it to be screwed to the steam-chest of an engine.

Within the oil-chamber is arranged a closely-fitting piston, D, having a tubular stem, d, which extends up through the cap A' of the oil-chamber and through an ordinary packing-gland, d'. The upper end of the piston-stem is cup-shaped and flanged, and the cup-shaped portion d' is covered by a cap, E, which is swiveled to an adjusting-screw, F, working through a yoke, G. The yoke G is provided at one end with a perforation, g, and at the other with a slot, g', as shown in Fig. 3, and a screw, g'', passes through the perforation g, and, in connection with another screw, g', which engages with the slot g', serves to secure the yoke to the flange d'. By loosening the screw g' the yoke may be turned around on the screw g'' as a pivot, carrying with it the swiveled cap E, so as to enable oil to be poured into the cup-shaped part d' to fill the oil-chamber. A small tube, V, supported at its upper end by a cross-bar, V', extends down through the piston-stem into the oil-chamber, and affords a vent for the escape of air from the latter when filling in the oil.

It is a passage extending from at or near the bottom of the oil-chamber below the piston, preferably up through the wall of the said chamber to near the top thereof, and thence downward a short distance and opening into the steam-space, C. A valve, I', controls the opening and closing of said passage.

J is another passage, of larger bore than passage I, leading from the steam-space C to the upper part of the oil-chamber above the piston, and having a valve, J', as shown. K is a pet-cock arranged in the cap of the oil-chamber.

The device being connected to the steam-chest of an engine and the valves I' J' closed, the pet-cock K is opened and the piston is drawn to the top of the oil-chamber into the position shown in Fig. 1. The pet-cock is then closed again, the yoke G swung around, and oil poured into the cup-shaped part d² until the oil-chamber below the piston, as well as the tubular piston-stem, is filled. The yoke G is then swung back and secured and the swiveled cap E clamped tightly to its seat by the adjusting-screw F. The valves I' and J' are then opened, so that by the pressure of steam on opposite sides of the piston—exerted on the one hand through the passage I and on the other through the passage J—the oil therein and in the body of the oil-chamber will be counterbalanced, and thus enable the mere weight of the piston and its connections to cause the piston to descend and feed the oil slowly but uniformly from the passage I into the steam-space C, and thence into the steam-chest; or the valve J' may be opened, so as to give a greater and overbalancing pressure of steam on the upper surface of the piston, and thus cause the latter to descend by such overbalancing pressure, in addition to its weight; but whether the mere weight of the piston or the overbalancing pressure of steam be relied upon to effect the descent of the piston, the quantity of oil fed into the steam-space can be regulated by the proper adjustment of the valves I' and J', as will be readily understood. The piston gradually descends until all the oil is forced out of the oil-chamber, whereupon the valves I' J' are closed, the pet-cock K again opened to let out the steam above the piston, the yoke G swung around, the cap E lifted, and the piston again raised to the top of the chamber, whereupon the chamber is refilled as before.

The outer case or shell, B, it will be observed, is made in two parts, b' b², united by a screw-connection, and the oil-chamber and part b' are both preferably cast together in one piece. The lower part, b², of the case is made concave, so as to collect the oil fed to the steam-space and direct it into the tubular central stem at the bottom.

By surrounding the oil-chamber with the steam-space it is kept highly heated and condensation of steam within it is prevented.

I do not, of course, desire to confine myself to any special form or dimensions of parts, as they may be varied to suit the ideas of the constructor. When more than the usual quantity of oil is required for one run a supplementary oil-reservoir, S, (shown in Fig. 2,) may be screwed onto a screw-neck, n, on the upper end of the piston-stem; but ordinarily the

use of such supplementary reservoir will not be necessary.

In Fig. 5 I have shown a modification of the means for feeding the oil into the oil-chamber under the piston, wherein the hollow piston-stem is stationary and the piston only moves, a suitable vent pipe or pipes, V², being attached to the piston for permitting the escape of air in filling.

The method of oiling automatically by means of the oil-cups in present use on locomotives is defective, because no oil is fed when the steam is cut off from the steam-chest and the locomotive is running downgrade; but the parts, not being lubricated even by the steam, become dry and rub, and soon wear so much as to require replacement. With a view to remedying this defect I have discovered what I deem a radical improvement in the art of oiling, which improvement I am enabled to readily carry out by the aid of my oil-cup herein described. It has been seen that the automatic operation of said oil-cup is effected by the pressure of the steam in the steam-chest, and it is therefore apparent that when the steam is cut off the oil will cease to be fed unless some means of maintaining a pressure in the steam-chest be provided. Now, I have discovered that by simply reversing the valves by the ordinary appliances, after the steam has been cut off, so that the piston in the cylinder, instead of exhausting or drawing from the steam-chest, will pump air into the same, a pressure of air will be maintained in the steam-chest sufficient to operate the oiling devices and secure the requisite feed of oil.

The value of this improvement and discovery will at once be appreciated by locomotive engineers, for, however long the grade may be down which the locomotive is running with steam cut off, a proper quantity of oil will be constantly supplied by the oil-cup for the efficient lubrication of the valves, &c.

Having thus described my invention, I claim as new—

1. In an oil-cup, an oil-chamber jacketed and heated by steam to prevent condensation, and having a piston operated by gravity or other equivalent force to insure the feeding of the oil, with oil supply and discharge openings or passages, and with suitable provision for substantially balancing the steam-pressure on each side of the piston, substantially as described.

2. In an oil-cup, an oil-chamber jacketed and heated by steam, a piston adapted to fit within said chamber, a passage or passages leading from said chamber below the piston to the steam-chest or part to be lubricated, and a passage or passages for the admission of steam above said piston, substantially as described.

3. In an oil-cup, an oil-chamber arranged within an outer casing or shell, so as to leave a steam-space between the two communicating with the steam-chest or part to be lubri-

- cated, a piston adapted to fit within said chamber, and passages leading from the steam-space to the oil-chamber above and below said piston, substantially as described.
- 5 4. In an oil-cup, an oil-chamber arranged within an outer casing or shell, so as to leave a steam-space between the two, a piston adapted to fit within said oil-chamber, means for feeding oil into the oil-chamber below the piston, and passages leading from the oil-chamber above and below the piston to the steam-chest or part to be lubricated, substantially as described.
- 10 5. In an oil-cup, an oil-chamber jacketed and heated by steam, a piston adapted to fit within said chamber, a passage or passages leading from the lower part of said chamber to the steam-chest or part to be lubricated, a passage or passages leading to the upper part 20 of said chamber for the admission of steam to the upper side of the piston, and valves for opening and closing said passages more or less, at will, to regulate the quantity of oil fed, substantially as described.
- 15 25 6. The combination of the oil-chamber, the piston having the tubular stem, and the vent-pipe, substantially as described.
7. The oil-chamber inclosed by the outer casing or shell, and having the valved passage leading above the piston to the steam-space and the valved passage leading from below the piston up through its vertical wall and thence into the steam-space, substantially as described, for the purpose specified.
8. The herein-described discovery and improvement in the art of lubricating the wearing-surfaces of locomotive steam-engines and other similar engines—to wit, by the employment of a lubricating mechanism normally operating under a substantially-balanced steam-pressure, in the manner substantially as herein described, and, when the locomotive is running with the throttle-valve closed, reversing the valves so as to cause the engine to substitute a balanced air-pressure upon the lubricating mechanism in place of the normal steam-pressure, substantially as herein set forth.

SAMUEL G. CABELL.
